FIG. 1.

FIG. 2.

FIG. 3.

FIG. 5.

FIG. 4.

GEORGE H. VAN VALKENBURGH
INVENTOR
BY *George H. Moore*
ATTORNEY

UNITED STATES PATENT OFFICE.

GEORGE HANSON VAN VALKENBURGH, OF NASHVILLE, TENNESSEE.

FILING DEVICE.

Application filed October 19, 1925. Serial No. 63,383.

My present invention relates to improvements in filing devices which while capable of use for various purposes is especially designed to provide a counter prescription-file 5 for pharmacists and others. The invention is embodied in an article of convenient size and shape to rest upon the counter, table or other support, to receive the prescriptions or other papers to be filed, and to 10 maintain them in orderly arrangement where they are readily accessible when required for use. The invention contemplates the use of a device having a separable member or file-holder which member may be 15 moved bodily from the device and replaced therein for transfer of contained files or prescriptions therefrom, and this member is also adapted for use with permanent filing devices in transferring the files to the latter 20 devices.

The invention consists in certain novel combinations and arrangements of parts as will hereinafter be more fully set forth and claimed.

25 In the accompanying drawings I have illustrated one complete example of the physical embodiment of my invention, and its uses, in which the parts are combined and arranged in accordance with the best mode 30 I have thus far devised for the practical application of the principles of my invention.

Figure 1 is a top plan view of the device of my invention.

35 Figure 2 is a vertical sectional view at line 2—2 of Figure 1.

Figure 3 is a view in elevation showing a portion of the device in position for transferring files.

40 Figure 4 is a view illustrating the file-holder detached from its base and used with a pin of a loose-leaf permanent file showing the manner of transferring files from the holder.

45 Figure 5 is an enlarged detail view partly in section showing the relation of the lower end of the post of the file-holder to the transfer pin in Figure 4.

In carrying out my invention I utilize a 50 base member 1 of suitable size and shape, which may be cast from metal and is fashioned with a lower flange 2 designed to rest upon the counter, desk, table or other support. At the under side of the base plate 1 are provided two bosses 3 and 4 preferably

cast integral with the plate and spaced a suitable distance apart. The boss 4 is designed to support the file-holder which is made up of wire, preferably of steel and properly fashioned to shape by means of 55 tools or machines. The file holder comprises a rigid straight post 5 having an acute angle or bend 6 and a resilient arm 7, the bend being designed to act as a separator for prescriptions or other papers on the file. 60 Thus in order to gain access to a desired prescription filed on the post 5, the prescriptions above the desired one are lifted and turned over the bend 6 to the arm 7 in vertical position, while the desired prescription 70 remains in horizontal position where it may be consulted with convenience.

The usual point 8 is fashioned at the end of the resilient arm 7 for penetrating the paper files or prescriptions as they are 75 entered on the file holder.

The separable file holder is secured to the base by means of its post 5 which is adapted to be inserted in the socket 9 of the retaining boss 4 and this boss also has a horizontally extending threaded socket 10 adapted to receive the screw 11 for clamping the file holder through its post in rigid position. The screw 11 passes through an opening 12 in the flange 2 of the base and its head 13 85 is located outside the hollow base for ready access in securing or releasing the separable holder in the base.

The resilient arm 7 of the file holder is held by the post 14 and its hook, or bent 90 upper end 15 in well known manner, and this retaining post which is threaded at its lower end 16 is screwed into the threaded socket 17 of the boss 3.

For storing or shipping the several parts 95 of the filing device may be separated and a compact arrangement of them made, while with equal facility the parts may be assembled in proper relative positions for use and the resilient arm 7 snapped under the hook 100 15 for retaining the file holder in normal condition, after a prescription or other paper has been filed. By depressing the pointed end of the resilient arm it may be detached from its retaining hook for filing 105 papers in usual manner.

In Figure 5 it will be seen that the lower end of the post 5 is recessed as at 18 in the form of a conical bore for the reception of the pointed end 19 of a pin 20. The pin 110

20 may be part of a permanent, loose-leaf file or book, and when the file holder is separated from its base and applied to this pin as indicated in Figure 4 the files or prescriptions may readily be transferred from the post 5 to the pin as indicated.

In Figure 3 the file holder has been removed from the base, reversed, and its pointed end is clamped by means of the 10 screw 11. In this manner the prescriptions on the post 5 may be removed therefrom in regular order and pasted in a book for preservation.

Having thus fully described my invention, 15 what I claim as new and desire to secure by Letters Patent is—

A filing device of the character described, consisting of a flanged base, a threaded boss depending from said base near one end there-

20 of, a post having a lower threaded end engaging said threaded boss and having a hook at its upper end, a boss at the other end of said base and depending therefrom and having a vertical smooth opening and also having a horizontal threaded opening at right 25 angles to said smooth opening and communicating therewith, a file holder having a vertical arm fitting in said smooth opening and formed with an arm to engage said hook of the post, and a screw having at one end a handle and having its other end threaded to engage said horizontal threaded opening and file holder to retain the file holder in place and mounted intermediate of its length 30 in the flange of the base.

35 In testimony whereof I hereunto affix my signature.

GEORGE HANSON VAN VALKENBURGH.
